United States Patent Office.

WILLIAM H. LAUBACH, OF PHILADELPHIA, PENNSYLVANIA.

Letters Patent No. 77,156, dated April 21, 1868.

IMPROVED APPARATUS FOR CARBONIZING GAS.

The Schedule referred to in these Letters Patent and making part of the same.

TO ALL WHOM IT MAY CONCERN:

Be it known that I, WILLIAM H. LAUBACH, of the city of Philadelphia, and State of Pennsylvania, have invented an Improved Apparatus for Carbonizing Illuminating-Gas; and I do hereby declare that the following is a full, clear, and exact description of the same, reference being had to the annexed drawing, and the letters of reference marked thereon.

The nature of my invention consists of an apparatus by which ordinary illuminating-gas is intimately and effectually mixed with the vapor of volatile oils or other substances rich in carbon, and which are evaporated at a low temperature, in connection with a glass gauge-tube, (which indicates the surface-level of the fluid in the chamber of said apparatus,) as hereinafter described.

To enable others skilled in the art to make and use my invention, I will proceed to describe its construction and operation.

It will be composed of tin or other suitable metal, and is intended to be attached to a gas-pipe, between the meter and burners.

Figure 1 is a perspective view of the outside of the apparatus, with the glass gauge-tube and supply-tube in section.

Figure 2 is a horizontal section through the red line $a' b'$, fig. 1.

Figure 3 is a sectional elevation through the red line $c' d'$, fig. 1.

Similar letters designate similar parts in all the figures.

To the side and top-plates of an ordinary oblong case, A, fig. 1, are fixed across inside, parallel to each other, the division-plates $a a$, &c., fig. 2, each being attached alternately to the opposite side-plates, and all being attached to the top-plate, fig. 3. They extend nearly to the bottom-plate, and are about two-thirds of the width of the case, so that an opening of about one-third the width is left between the edge of each plate and the opposite side-plate.

To the bottom-plate are attached, parallel to each other, and across the said casing, the division-plates $b b$, &c., figs. 2 and 3, extending nearly to the top-plate, but about being only half the width of the casing, and placed in the middle of the bottom-plate. An open space is left at each edge of the said plates, between it and the sides of the casing. These division-plates are placed in the centre of the spaces left between the plates $a a$, &c.

The chamber B, figs. 2 and 3, in the interior of the casing, is thus subdivided into numerous cells or passageways, communicating with each other by the spaces left between the edges of the division-plates and the sides, top, and bottom of the casing. These are again subdivided by loosely placing muslin or other fibrous material, $c c$, &c., figs. 2 and 3, between the division-plates, by which arrangement the gas flowing through the chamber B is made to traverse all the divisions thus formed.

The open ends of the glass gauge-tube C, fig. 1, which is hollow, fit into sockets in the caps $f f$, and are pressed tightly against the leather packing-rings $i i$, by means of the strap $d d$, (which passes around them,) and set-screw e , inserted into a cap attached to the upper ends of the said strap. Thus the said gauge-tube is held firmly in place, and attached to the caps $f f$, which are fastened to the tubes $g g$, inserted into the top and side of the casing A, and thus a free communication is always secured between the hollow in the said gauge-tube C and the chamber B, figs. 2 and 3, by means of the openings $n n$, through the leather packing and inner rings of the caps $f f$, and the tubes $g g$; consequently, the surface-level of the fluid in chamber B and that in the interior of the glass gauge-tube C are the same.

The strap $d d$ forms a guard to the glass tube C; and the upper tube, g , is made long, so as to allow of sufficient spring or vibration to admit of tightening the gauge-tube joints. There are also a supply-tube, F, an inlet-tube, D, and an outlet-tube, E, inserted in and attached to the top-plate of the casing.

Agreeably to the above description, the apparatus being attached to the gas-pipe as before mentioned, and the chamber B being partly filled with the proper fluid through the supply-tube F, which is then closed, the

gas, under the ordinary pressure, is introduced into the chamber B, through the inlet-pipe D, and in its passage is made to traverse, in an attenuated stream, through all the passages into which the said chamber is divided, and thus comes in contact with the fluid and vapor contained therein, and is effectually carbonized by the large proportion of the vapor which it absorbs. It then passes, through the outlet-pipe E, into the pipe for supplying the burners, its illuminating-power being largely increased at a very trifling cost.

I do not claim the closed chamber B, with fibrous material, nor the zigzag passages, as these are described in the patents of J. F. Boynton, September 25, 1866, and October 8, 1867; but

What I do claim is—

The hollow glass gauge-tube C, caps f f, straps d d, set-screw e, and tubes g g, in combination, made in the manner and for the purpose described.

W. H. LAUBACH. [L. S.]
